UNITED STATES PATENT OFFICE

2,535,725

PLATE POSITIONING MEANS IN PRINTING MACHINES

Franklin E. Curtis, Willoughby, Ohio, assignor to
Addressograph-Multigraph Corporation, Wil-
mington, Del., a corporation of Delaware

Application August 7, 1946, Serial No. 688,823

2-Claims. (Cl. 101—297)

1

This invention relates to printing machines and more particularly to printing machines of the hand operated type.

It is the primary object of my invention to construct a printing machine with which a complete printed record both of an article issued and the person to whom the article is issued may be quickly and easily made in a simple operation.

It has long been the custom in stores, libraries, factory tool cribs and the like, to make a hand-written record of the article sold or checked out and the name and address, or other identification, of the person to whom the article was sold or checked out. This procedure has many inherent disadvantages including the disadvantage that such a procedure is relatively slow. Also, such procedure presents considerable opportunity for human error to creep into the copying of such information, which destroys the accuracy and reliability of such records. A further disadvantage also involves a human factor, namely, that records or receipts written by hand are often illegible.

It is an object of my invention to construct a printing machine which overcomes these disadvantages and, in this connection, it is an object of my invention to construct a printing machine whereby a printed record of the article sold or checked out, and the customer to whom the article was sold or checked out may be made in one simple operation of the machine from a previously prepared article-identifying printing device and a previously prepared customer-identifying device, both of which are inserted into the machine for the single printing operation.

Another object of my invention is to construct a printing machine whereby a printed record of an article sold or checked out and the customer to whom the article is sold or checked out may be made without danger of manual copying errors.

A further object of my invention is to construct a printing machine of this character which will simply and easily produce a completely legible printed record of a sale or check-out transaction.

In order that the record cards be properly printed the printing devices must be properly positioned in the printing machine, and another object of my invention is to so construct a printing machine that accuracy in positioning of the printing device is assured.

An object ancillary to the foregoing object is to so construct a printing machine that, when printing devices are associated therewith for the

2

purpose of preparing a record card, improper positioning of the printing devices is readily apparent so that it may be corrected before operating the printing machine.

Other and further objects of the present invention will be apparent from the following description and claims and are illustrated in the accompanying drawings which, by way of illustration, show preferred embodiments and the principles thereof and what I now consider to be the best mode in which I have contemplated applying these principles. Other embodiments of the invention embodying the same or equivalent principles may be used and structural changes may be made as desired by those skilled in the art without departing from the present invention and the purview of the appended claims.

In the drawings:

Fig. 1 is a top plan view of a printing machine embodying the principles of my invention;

Fig. 2 is a side elevational view of the machine shown in Fig. 1;

Fig. 3 is a detail view with certain parts broken away, looking down on the anvil portion of the machine and showing two printing devices as they would be positioned in the machine when the machine is operated.

Fig. 4 is an illustration of one type of record card which may be prepared with my machine;

Fig. 5 is a detail view of a typical customer-identifying printing device used in my machine;

Fig. 6 is a detail view of a typical article-identifying printing device used in my machine;

Fig. 7 is a detail view similar to Fig. 3 but showing a modified form of my machine.

The printing machine shown in the accompanying drawings embodies a casing or base 16 mounted on feet or legs 11, and having side walls 12 and 13, a front wall 14, a rear wall 15, a top wall 16 and an open bottom. The walls may be made of any suitable material such as, for example, cast iron, and the top wall 16 has a channel 17 formed therein within which is positioned an anvil 18, which may be made of any suitable material such as steel and which, as will be described more fully hereinafter, supports the printing devices during operation of my machine. The anvil 18 may be constructed as a separate element and then fastened in the channel 17 of the top wall 16, by any suitable means such as screws.

An inked ribbon 19 is carried by two spools 20 and 21, and extends through the top wall 16 and across the anvil 18. The spools 20 and 21 are mounted on shafts 22 and 23, for rotation

therewith, and which shafts are journaled in the side walls 12 and 13. Knurled knobs 24 and 25 are mounted on one end of each of the shafts 22 and 23, respectively, and the operator may turn the knurled knobs 24 or 25 to thereby turn the spools 20 and 21 and position a fresh, unused portion of the inked ribbon 19 over the anvil 18 in printing position. Automatic ribbon advancing means may of course be employed if desired. Ribbon guards 26 and 27 are mounted on the upper surface of the top wall 16 and are secured thereto by screws or bolts 28 and 29, respectively, which extend through respective slots 30 and 31 in the ribbon guards 26 and 27. The slots 30 and 31 have enlarged portions formed therein so that by loosening the bolts 28 and 29 and sliding the ribbon guards 26 and 27 to the side until the heads of the bolts are in registration with the enlarged portions of the slots 30 and 31 the ribbon guards may be easily removed from the top wall 16 to facilitate the removal of an old ribbon 19 and the insertion of a new one.

A stamper arm 32 is rockably mounted on a shaft 33 which is journaled in ears 34 which extend upwardly from the rear portions of side walls 12 and 13. The stamper arm 32 is normally spring urged into retracted or raised position, Fig. 2, by a spring 35 one end of which is attached to a lug or extension 36 on the stamper arm 32, and the other end of which is attached to a pin 37 which is carried by and projects inwardly from the side wall 12.

A platen 38 is carried by the forwardly projecting head 39 of the stamper arm 32 and is so positioned that, by pressing down on the head 39, the operator may move the platen down into printing relation with the anvil 18.

A paper guide or marginal guide 40 having a guide arm 41 and a support bracket 42 is mounted on the base 10 and is adjustably secured thereto by a bolt which is carried by and extends outwardly from the wall 13 and extends through a slot 43 in the bracket 42. A knurled knob or nut 44 is threaded on to the bolt which extends through the slot 43 and may be screwed in to hold the bracket 42 in tight frictional engagement with the side wall 13 and thereby hold the marginal guide 40 in adjusted position. The purpose of marginal guide 40, as will be more specifically set forth hereinafter, is to serve as a guide or reference for the proper positioning of a record card, or the like, on which it may be desired to print certain data with my machine.

In the operation of my machine printing devices are placed on top of the anvil 18 below the inked ribbon 19. These printing devices may be previously embossed with the necessary or desired data in any suitable embossing machine such as, for example the machine shown and described in Duncan and Hubbard Letters Patent No. 1,831,103, patented November 10, 1931. When used in my machine, the previously prepared printing devices are so positioned on the anvil 18 that the face of the printing devices, on which the data to be printed by the printing machine appears in relief, faces upwardly or, in other words, is adjacent to the underneath surface of the inked ribbon 19, and the face of the printing devices, on which the data to be printed by the printing machine appears in intaglio, faces downwardly, or in other words, is adjacent to the upper face of the anvil 18. It will be noted that, inasmuch as the inked ribbon 19 is positioned between the printing devices and the record card upon which the data is to be printed, the data will be printed on the

face of the card as shown in Fig. 4 of the drawings.

The upper edges 45 and 46 of the anvil 18 extend above the bed thereof and form a closely fitting guideway which engages the edge portion of the printing devices used in my machine. Two pins 47 and 48 extend upwardly from the upper face of the anvil 18 in the center portion thereof and are positioned to engage a complementary groove or notch in a properly positioned printing device such as, for example, the grooves 49 and 50 formed in the end edge portions of the printing devices 51 and 52, respectively, Figs. 5 and 6.

It will be noted that in the operation of my printing machine the printing devices 51 and 52 are slid into the channel 17 from the opposite ends thereof into position over the anvil 18. The printing device 51, is properly slid into the channel 17 over the anvil 18 from the left, Fig. 1, and is guided by the sides 45 and 46 of the anvil 18 into position where the notch 49 engages the pin 47, and the printing device 51 is thereby guided into proper registration with the platen 38. The printing device 52 is properly slid into the channel 17 over the anvil 18 from the right, Fig. 1, and is guided by the sides 45 and 46 of the anvil 18 into position, where the notch 50 engages the pin 48 and the printing device 52 is thereby also guided into proper registration with the platen 38. When so positioned in my machine the left and right edges, Fig. 3, of the printing devices 51 and 52, respectively, are positioned inwardly of the respective end edges of the channel 17.

In this connection, it will be noted that, if the printing devices are inserted into printing relation with the ribbon 19, from the wrong end of the channel 17, or from the proper end of the channel 17 but wrong end first, the pins 47 and 48 will not engage in the notches 49 and 50 but will engage the end edges of the printing devices so that the printing devices will protrude from their proper printing position which will be apparent to the operator of the machine. Also it will be noted that if the printing devices 51 and 52 are inserted into the channel 17 from the correct ends thereof but are turned over in improper position, this will be readily apparent. Hence, it will be seen that the positioning of the printing devices 51 and 52 may be easily checked visually and any mispositioning thereof is readily detected.

In establishments where my printing machine is to be used such as for example in stores, libraries, or factory tool cribs, an article-identifying printing device (such as the printing device 52) has been previously prepared for each article which is available for sale or checking out and is on file near the machine. Likewise, a customer-identifying printing device (such as the printing device 51) has been prepared for each customer and is carried on the customer's person. When a sale or check-out is made and it is desired to make a record of the transaction, the following simple procedure is followed.

The article-identifying printing device 52 is withdrawn from the files by the attendant or clerk and is properly inserted into the printing machine 10 from the right side (as viewed in Fig. 1). The customer also presents his customer-identifying printing device 51 to the clerk or attendant and this is properly inserted into the printing machine 10 from the left side. The marginal guide rod 41 has previously been properly adjusted for the size record card or sales

check to be used, and the attendant now places the sales check or record card face down on the inked ribbon 19 with the left edge portion of the sales check or record card extending toward the right of the machine and the top edge of the record card in engagement with the marginal guide 41. The attendant then presses the head 39 of the stamper arm 32 down by hand, thereby moving the platen 36 into engagement with the record card and pressing the record card, and the inked ribbon 19 against both printing devices 51 and 52 simultaneously and thereby transferring the identifying data from both printing devices 51 and 52 simultaneously onto the record card in one single printing operation. The attendant then disposes of the record card or sales check in the usual manner, removes the article-identifying printing device from the machine and returns it to the files, and removes the customer-identifying printing device from the machine and returns it to the customer.

It will be apparent, of course, that, if desired, carbon copies of the sales check or record card may be prepared and simultaneously with the preparation of the original copy thereof.

Also, it will be noted that my printing machine may readily be used for making more complicated sales checks or record cards than the ordinary one-entry record card or sales check most generally used. For example, if, in a tool crib, library, or the like, it is desired to make up a multiple section record card so that one section may be placed in the files under the name of the tool, another section may be placed in the files under the name of the customer, and another section may be issued as a customer's receipt, this may easily be done with my machine by preparing a record card or sales check such as the record card 60.

The record card 60 embodies three sections, an article-file section 61, a customer-file section 62 and an employee receipt section 63. The article-file section is joined to the customer-file section 62 and the customer receipt section 63 along a perforated line 64. Likewise, the customer-file section 62 is joined to the customer receipt section 63 along a perforated line 65. If desired, the three sections of each record card may have a common identifying serial number 66 (the number being "936" on the card shown in Fig. 4) so that the various sections may be readily identified in the files.

In using this type of record card, the machine is prepared for operation in the manner heretofore discussed, and the record card is placed face down on the inked ribbon 19 with the left edge portion extending toward the right of the printing machine (as viewed in Fig. 1) and the top T of the card in engagement with the marginal guide arm 41, and with the article-file section 61 of the card registered in printing position over the printing devices 51 and 52. The printing operation is then performed by pressing the stamper arm 32 down. The card 60 is then moved to the right until the customer-file section 62 and the customer-receipt section 63 is in registration with the printing devices 51 and 52 and the printing operation is again repeated by pressing the stamper arm 32 down.

Hence, from the foregoing it will be noted that my machine may be readily utilized to easily prepare a multiple section record card, one section of which (section 61) may be filed in the article-identifying file, another section of which (section 62) may be filed in the customer-iden-

tifying file, and the other section of which (section 63) may be issued to the customer as a receipt.

A modification of my printing machine is illustrated in Fig. 7. It will be noted that my machine as modified in this manner operates in the same manner as the preferred embodiment of my invention, as heretofore described, and, therefore, it is believed that a description of the changes in structure of the proposed modification taken together with the foregoing description of the preferred embodiment of my invention will be sufficient to assure a complete understanding thereof. Also, it will be noted that in Fig. 7 parts similar to parts shown in Figs. 1 to 6, and previously referred to, are indicated by like reference numerals with the prefix "1" added.

In the modified form of my machine a strap member 70 having protuberances or dogs 147 and 148 is mounted on the anvil 117 of the machine and the dogs 147 and 148 are positioned so as to engage in notches 149 and 150, respectively, of printing devices 151 and 152, respectively, when the printing devices are properly positioned on the anvil 117.

From the foregoing it will be apparent that by using my machine an accurate, legible and complete printed record of each sale or check-out transaction can be made in one simple and quick printing operation. Also, it will be noted that my machine provides means whereby printing devices may be quickly and accurately positioned in proper printing position in the machine and that improperly positioned printing devices 35 may be readily detected. Furthermore it will be noted that use of my machine eliminates all danger of manual copying errors in the preparation of sales checks and record cards.

Hence, while I have illustrated and described the preferred embodiments of my invention it is to be understood that these are capable of variation and modification and I therefore do not wish to be limited to the precise details set forth, but desire to avail myself of such changes and alterations as fall within the purview of the following claims.

I claim:

1. A printing machine of the type adapted to be used in conjunction with a plurality of printing devices simultaneously, each printing device having a notch formed at a predetermined and different position in one end thereof, said printing machine comprising an anvil adapted to receive such printing devices from respective ends and to support said plurality of said printing devices simultaneously in predetermined printing positions wherein said printing devices are disposed within the peripheral boundaries of said anvil, a plurality of abutments mounted on and projecting from said anvil, each of said abutments being disposed in a position to enter the said notch in a corresponding one of said printing devices when said printing device is moved theretoward in predetermined relation to said anvil to thereby permit said printing devices to be disposed in a corresponding one of said printing positions on said anvil, said abutments also being disposed on said anvil in position to engage said printing devices exteriorly of said notches when said printing devices are moved toward said abutments in other than said predetermined relations to said anvil whereby said printing devices will have a portion extending outwardly beyond said anvil to indicate improper positioning, means for supporting a sheet and a platen adapt-

ed to be moved relative to said anvil to press said sheet into simultaneous printing relation with such a plurality of printing devices disposed in said printing positions.

2. The printing machine defined in claim 1 and in which said abutments are mounted on and project from a single abutment member removably mounted on said anvil.
